UNITED STATES PATENT OFFICE.

NELSON A. CARLSON, OF ERIE, PENNSYLVANIA, ASSIGNOR TO ERIE METER SYSTEMS, INC., OF ERIE, PENNSYLVANIA, A CORPORATION OF PENNSYLVANIA.

CONTROLLING MECHANISM FOR GASOLINE TANKS.

Application filed August 6, 1927. Serial No. 211,176.

Gasoline stations are ordinarily provided with a dispensing tank holding gasoline and air supplying means for putting pressure on the tank so that the gasoline is delivered to the dispensing point from the air pressure. In case of fire these pressures operating in connection with the gasoline supply are a menace and the present invention is designed to improve the construction by cutting off the pressure connections. Features and details of the invention will appear from the specification and claims.

A preferred embodiment, or exemplification of the invention is illustrated in the accompanying drawings as follows:—

Fig. 1 shows a side elevation of the mechanism.

Fig. 2 a central section through one of the controlling valves.

Fig. 3 a plan view of a portion of one of the controlling valves.

1 marks the dispensing tank, 2 an air receiver, and 3 an air pump.

The air receiver is connected to the tank by means of a pipe 4, a self-closing valve 5, a regulating valve 6, and a self-closing non-return valve 7 and pipe 8.

The valves 5 and 7 are of the same structure except that the parts are reversed and in Fig. 2 is shown a section of one of these valves in closed position, such valves being shown in open position in Fig. 1.

9 marks the valve body and 10 the valve seat. A valve head 11 operates on the seat and is supplied with guide extensions 12 which operate on the barrel in the valve body to actuate the head. A spring 13 yieldingly moves the valve to its seat. A pin 14 projects from the head 11 and is provided with a slot 15 at its end. An arm 16 operates in the slot 15. The arm is mounted on a squared portion 17 of a valve stem 18. A handle 19 is pivotally mounted on the stem 18 and adapted to turn the stem 17 to rock the arm.

45 16. By rocking the arm 16 the valve 11 may

be opened against the force of the spring. A fusible link 21 is secured to the body by a screw 22. This link has a shoulder 20 which is engaged by the handle 19 so as to lock the valve in open position. When the valve is subjected to any temperature above that of fusing the link is fused and the valve is instantly closed through the action of the spring and held closed through the pressure. Safety valves 23 extend from the body 9 and pressure gauges 24 also extend from the body of the valves, this forming a convenient mounting for these parts.

In case of fire and a temperature raising the fusing temperature of either link this particular valve is closed. Thus the high pressure air is automatically closed against the gasoline tank and if the gauges and differential valve 6 should be injured the non-return valve 7 will prevent an escape of vapors from the tank and thus minimize the danger. The structure permits of carrying, therefore, somewhat higher pressure on the tank 2 than would ordinarily be advisable.

What I claim as new is:—

1. In a controlling mechanism for gasoline tanks, the combination of a pressure fluid supply means; a conduit leading from the means to the tank; a self-closing valve in the conduit; and thermally controlled devices securing the valve in open position and releasing the same under abnormal heat.

2. In a controlling mechanism for gasoline tanks, the combination of a pressure fluid supply means; a conduit leading from the means to the tank; a valved mechanism controlling the conduit against flow through the conduit in both directions; and thermally controlled devices controlling the mechanism to maintain the conduit in open condition and releasing said mechanism to close the conduit under abnormal heat.

In testimony whereof I have hereunto set my hand.

NELSON A. CARLSON.
